UNITED STATES PATENT OFFICE.

TRUMAN H. ALDRICH, OF CINCINNATI, OHIO, ASSIGNOR OF ONE-HALF TO
A. G. ROSE, OF SAME PLACE.

BLOW-PIPE.

SPECIFICATION forming part of Letters Patent No. 469,670, dated March 1, 1892.

Application filed April 2, 1891. Serial No. 387,346. (No model.)

To all whom it may concern:

Be it known that I, TRUMAN H. ALDRICH, a citizen of the United States, residing at Cincinnati, in the county of Hamilton and State 5 of Ohio, have invented a certain new and useful Improvement in Blow-Pipes, of which the following is a specification.

My invention relates to blow-pipes, more especially to blow-pipes for dental uses. It 10 is usual for dentists to remove the cuttings or chips made by the excavator or drill from the cavity and to dry the tooth by means of a blast of heated air. In dental blow-pipes as heretofore constructed the air has been 15 heated by passing it through a chamber heated by exposure to a flame. This mode of heating is objectionable, because the chamber is slow to heat, and when removed from the flame rapidly cools, requiring frequent 20 reheating and consequent delay in the operation. It is further objectionable because the heat is greatest at the surface and the instrument is likely to come in contact with and burn the face of the patient.

25 It is the object of my invention to avoid these objections; and it consists in the combination and arrangement of parts hereinafter specified.

In the drawings, Figure 1 represents a side 30 elevation, partly in section, of my improved apparatus; and Fig. 2, an enlarged view in section of one of the binding-posts for the conductor.

A is a tube provided at one end with an 35 annular cap B, to which an elastic bulb C, provided with an inlet-valve c, may be secured. The other end of the tube is preferably spun to a point, forming an injection-nozzle D. In the interior of the tube A, I 40 place a substance adapted to be electrically heated, preferably a coil of wire E, one end of which may be secured to a screw F, taking through the tube and attached thereto by a nut f. The other end of the wire may 45 take between the head g of a screw G and a washer g', taking over the latter, the screw G taking through an aperture a in the tube and being held in place by a nut g². The screw G is electrically insulated from the 50 tube. This may be accomplished by enlarging the aperture a sufficiently to allow the screw G to take therethrough without con-

tacting with the tube and by providing washers g³ g⁴, of non-conducting material, one of which is adapted to take between the tube 55 and washer g' and the other between the tube and nut g². Wires h h', connected to a battery or other source of electricity H, are adapted to be joined, respectively, to the screws F and G and form electrical connection with the coil E. The wires may be held in place by nuts f' and g⁴, taking, respectively, over the screws F and G, thereby forming binding-posts for the same.

I is a switch adapted to break the electric 65 circuit. I prefer to separate the electrically-heated substance from the tube by a layer K of non-heat-conducting material, such as asbestos or other material which will yield somewhat to compensate for expansion. It is de- 70 sirable that the conductor in the tube be heated and the wires connecting with the source of electricity remain practically unaffected by the electric current. I therefore employ a conductor in the tube of greater 75 electric resistance than the wires connecting with the electric source.

In my improved device the surface over which the air or other matter passes is heated immediately upon the closing of the 80 electric circuit and retains a uniform heat indefinitely. The operator is in no danger of coming in contact with heated surfaces or burning the patient, as is the case with the old devices.

I claim—

The combination, in a dental blow-pipe, of a tube, an injection-nozzle at the end thereof, a source of electricity, connections between the source of electricity and contacts within 90 the tube, an electric conductor taking from one contact through the tube in the form of a cylindrical coil and returning through itself to the other contact, a non-heat-conducting elastic packing between the coil and the 95 wall of the tube, and an elastic bulb or equivalent means attached to the tube and adapted to force a current of air therethrough, substantially as and for the purpose specified.

TRUMAN H. ALDRICH.
